MOTOR DRIVEN HEADSTOCK FOR MACHINE TOOLS

Albert W. Wigglesworth, Chicago, Ill., assignor to
 Hill-Clarke Machinery Co., Chicago, Ill., a corporation of Illinois

Application February 3, 1936, Serial No. 62,079

5 Claims. (Cl. 51—237)

This invention relates to machine tools and particularly to a motor driven headstock for grinding machines. Such machines comprise a longitudinally reciprocable work carriage on which the headstock and tailstock, i. e. the work supporting and rotating mechanism are carried, for moving the work past a grinding tool located in juxtaposition to the carriage.

The main object of the invention is to produce a self-contained enclosed headstock unit provided with variable speed, motor actuated driving means and mounted on the work carriage to travel with the carriage.

Another object is to provide means for adjusting the tension of the belt which transmits power from the motor shaft to the drive mechanism without shifting of the motor.

Another object is to provide manually actuated means for varying the speed of rotation of the head stock center, which means may be actuated while the motor is in operation.

In the drawings:

Fig. 1 is a front elevation of part of a grinding machine embodying my improved headstock.

Fig. 2 is a rear elevation of the same.

Fig. 3 is a sectional view taken on the line 3—3 of Fig. 4.

Fig. 4 is a plan view of the headstock, with the cover of the housing removed.

In that embodiment of the invention shown in the drawings, the base 13 of the machine supports a longitudinally slidable work carriage 11 on one end of which is carried the headstock which cooperates with a tailstock, not shown, to support the work.

The headstock comprises a two-piece lower housing 12, 13, supports 14, 14 connected to the part 12 of the housing, and a two-piece upper housing 15. In the upper housing 15 are mounted a motor 16, pulley supporting frame 17, and grooved pulley 18 and plain wide pulley 19 on a shaft 20. The motor 16 is fixedly mounted on the floor 21 which partially closes the bottom of the housing 15. Spaced apart brackets 22 on the floor 21 support a horizontal shaft 23 on which is pivotally mounted the frame 17. The upwardly curved arms 24 of the frame 17 are apertured at their upper ends for the reception of the pulley shaft 20 rotatably mounted therein. The pulley 18 is fixed on one end of the shaft 20 and the wide pulley 19 is fixed to said shaft between the arms 24 of the frame 17. One of the arms of the frame 17 is extended beyond the shaft 23 as indicated at 25 and is apertured to receive an adjusting screw 26. A depending lug

27 on said arm is apertured for the reception of an adjusting screw 28. The adjustment of the screws 26 and 28 in the end 25 and lug 27, respectively, with their ends bearing on the floor 21 of the housing, swings the frame 17 relatively to the shaft 23 and thus varies the position of the pulley 18 for the purpose of adjusting the tension of the belt 29.

The belt 29 on the pulley 18 of the motor shaft transmits power from the motor 16 through pulley 18 to shaft 20. A belt 31 on the wide pulley 19 on said shaft 20 extends through the open bottom of the housing 15 and transmits power to the drive shaft 32 through the speed-change pulley 33 on said shaft 32. The shaft 32 is operatively connected with the rotatable headstock center 34 through gearing (not shown) located in the lower housing member 13.

The speed change is accomplished by moving the belt 31 longitudinally of the wide pulley 19 and stepped or cone pulley 33. For this purpose I have provided a forked slide member 35 through which one lap of the belt 31 extends. The member 35 is slidably mounted on a shaft 36 in the housing 15, parallel with the pulley shaft 20, and has a handle 37 on its outer face and a pin 38 adapted to engage notches 39 in a bar 40 fixed to the housing 15. By tilting the slide member 35 it may be disengaged from one of the notches 39 in the bar 40 and be moved longitudinally of the bar to another notch.

In order to permit the belt 31 to be moved by actuation of the slide member 35, it is necessary to relieve the belt 31 of tension and this is accomplished by pressing downwardly on a lever 42 rigidly connected to the part 43 of the housing 13 and arm 44, said housing and arm being pivotally mounted on the shaft 45 which is in alignment with the center 34. The arm 44 terminates in a bearing for the shaft 32. The downward actuation of the lever 42 and pivotal movement of the arm 44 (the latter being pivotally connected with shaft 32), raises the shaft 32 and the change-speed pulley 33 and relieves the belt 31 of tension, so that it may be moved on the pulleys 19 and 33 to vary the speed of the shaft 32 which is geared to the center 34 to rotate it. When the lever 42 is released after adjustment of the belt 31 on pulleys 19 and 33, the pulley 33 with shaft 32 and associated housing 13 move by gravity to the position shown in Fig. 3 in which the belt 31 is under proper tension for operating purposes. The handle 46 is a locking device for preventing unintended movement of the lever 42, arm 44 and

shaft 32, and must be released before the lever 42 can be depressed.

I have described the center 34 as a live center, rotatably connected with the drive shaft 32, but 5 obviously it may be a dead center and have mounted on it a work driving plate fixed to a gear rotatably mounted on the center or its spindle, the gear being driven by the drive shaft 32.

An advantage of the described construction is 10 the fact that the enclosed, self-contained headstock unit protects the motor and driving belt from water.

Changes may be made in details of construction 15 without departing from the scope of my invention and I do not intend to be limited to the exact form shown and described, except as set forth in the appended claims.

I claim:

1. A motor driven headstock for grinding machines having a longitudinally movable work carriage, said headstock comprising a motor, a motor shaft, a rotatable pulley shaft operatively connected with the motor shaft, a housing mounted on the carriage and containing said 25 motor, motor shaft and pulley shaft, a drive shaft parallel with the pulley shaft, speed change elements on one of said shafts, a belt connecting said shafts, a work-engaging member, operative connections between the drive shaft and 30 work-engaging member, a two part housing, mounted on the carriage, supporting the drive shaft and work-engaging member and enclosing said operative connections between them, and means on said two part housing for pivotally moving part of the housing and thereby bodily moving the drive shaft to release tension on said belt.

2. A grinding machine comprising a longitudinally reciprocable work carriage and a head- 40 stock unit mounted on the upper side of the work carriage to travel with the carriage, said headstock comprising a motor, a pulley operatively connected with the motor, a raised support on the carriage for the motor and pulley, a drive shaft, speed change elements on the drive shaft, pivotally mounted supports on the carriage, said drive shaft being rotatably mounted in said pivotal supports in a position beneath the pulley, means for actuating the pivotal supports to raise and lower said drive shaft, a belt connecting the pulley and the drive shaft, a work engaging member, the axis of which is parallel with the direction of movement of the carriage, and operative connections between the 50 drive shaft and the work engaging member.

3. A grinding machine comprising a longitudinally reciprocable work carriage and a head-

stock unit mounted on the upper side of the work carriage to travel with the carriage, said headstock comprising a motor, a pulley operatively connected with the motor, a raised support on the carriage for the motor and pulley, 5 a drive shaft, speed-change elements on the drive shaft, supports on the carriage in which the drive shaft is rotatably mounted, means for raising and lowering the drive shaft, a belt connecting said drive shaft and pulley, a work engaging member parallel with the drive shaft and having its axis parallel with the direction of movement of the carriage, and operative connections between the drive shaft and work engaging member. 10 15

4. A motor driven headstock for grinding machines having a longitudinally movable work carriage, said headstock comprising a motor, a motor shaft, a rotatable pulley shaft operatively connected with the motor shaft, a housing mounted on the carriage and containing said motor, motor shaft and pulley shaft, a drive shaft parallel with the pulley shaft, speed change elements on one of said shafts, a belt connecting said shafts, a work-engaging member, operative connections between the drive shaft and work-engaging member, a second housing, mounted on the carriage, supporting the drive shaft and work-engaging member and enclosing said operative connections between them, 30 and a belt-engaging member slidably mounted on the first mentioned housing for moving the belt longitudinally of said pulley shaft and drive shaft. 20 25

5. A motor driven headstock for grinding machines having a longitudinally movable work carriage, said headstock comprising a motor, a motor shaft, a rotatable pulley shaft operatively connected with the motor shaft, a housing mounted on the carriage and containing said 40 motor, motor shaft and pulley shaft, a drive shaft parallel with the pulley shaft, speed change elements on one of said shafts, a belt connecting said shafts, a work-engaging member, operative connections between the drive shaft and work-engaging member, a second housing, mounted on the carriage, supporting the drive shaft and work-engaging member and enclosing said operative connections between them, a belt-engaging member slidably mounted on the 45 first mentioned housing for moving the belt longitudinally of said pulley shaft and drive shaft, and means on the second housing for bodily moving the drive shaft to relieve the belt 50 of tension while said belt-engaging member is 55 being slidably actuated.

ALBERT W. WIGGLESWORTH.
